TREASURE CHEST

Al Petker, Los Angeles, Calif.

Application April 22, 1954, Serial No. 30,130

Term of patent 14 years

(CL. D58—11)

FIG. 1.

FIG. 2.

FIG. 3.

To all whom it may concern:

Be it known that I, Al Petker, a citizen of the United States, residing at Los Angeles, in the county of Los Angeles, State of California, have invented a new, original, and ornamental Design for Treasure Chest, of which the following is a specification, reference being had to the accompanying drawings forming part thereof.

Fig. 2 is an end view of the same;

Fig. 3 is a plan view; and

Fig. 4 is a rear view.

The end view not shown is the same as the end view shown.

I claim:

The ornamental design for a treasure chest, as shown and described.
